(57) **CLAIM**

The ornamental design for a compact motor reducer, as shown and described.

DESCRIPTION

1. Compact motor reducer

1.1: is a front view;

1.2: is a left view;

1.3: is a right view;

1.4: is a back perspective view;

1.5: is a top plan view;

1.6: is a back view; and

1.7: is a front perspective view.
